DISPENSING CONTAINER

Roy L. Peck, Portland, Oreg.

Application February 14, 1933, Serial No. 656,706

10 Claims. (Cl. 206—57)

The invention is primarily intended for the dispensing of interfolded sheets of paper toweling. The dispensing container is preferably made from a single piece of fibrous material as paper.

5 I place the interfolded sheets in the container and leave the broad surface of the sheets in a vertical plane, the object being to provide a method of dispensing the sheets from the side of the pack thereby to prevent the weight of the 10 superposed pack being distributed to the sheet that is to be dispensed.

I provide a placement flap at the bottom of and remote from the dispensing wall of the container, the primary object and purpose of the 15 flap being to maintain the sheets in position and to prevent the simultaneous emergence of a plurality of the same from the dispensing container.

20 I score one side of the dispensing container adjacent its lower edge with parallel scored lines. That portion of the wall embraced within the scored lines is to be broken away and removed by the user of the device. I slit a pair of supporting ears from the top wall of the container 25 and provide holes therein to facilitate the suspension of the carton in position upon any suitable supporting wall surface.

The primary purpose and object of my invention is to provide a dispensing carton for the 30 storing and dispensing of interfolded sheets of paper, as paper toweling or paper napkins.

Another object of my invention consists in providing a dispensing carton made of fibrous material, as paper, and in which the interfolded 35 sheets of paper may be stored and shipped and which are sealed within the carton prior to the storing and shipping process. My dispensing carton has a dispensing opening outlined upon a broad side and adjacent the lower edge thereof. 40 The outline of the dispensing opening is scored along its broad edges and at its ends to permit the removal of that portion of the carton embraced within the rectangle formed by the scored lines to form a dispensing opening through which 45 the contents of the dispensing carton may be withdrawn one at a time.

A still further object of my invention consists in providing a dispensing carton for sheets of paper that may be discarded after its contents 50 have been withdrawn therefrom one sheet at a time.

A still further object of my invention consists in providing a retaining placement flap adjacent the dispensing opening in the carton that aids in maintaining the interfolded sheets in position and

5 prevents the withdrawal of more than one sheet at a time.

A still further object of my invention consists in so placing the interfolded sheets within the carton that there is no superposed weight upon 5 any of the sheets that are to be withdrawn from the dispensing carton.

A still further object of my invention consists in providing means whereby sheets of paper may be packed within a dispensing carton and be 10 thereafter untouched until withdrawn by the user.

A still further object of my invention consists in the placing of supporting ears from one of the primary walls of the container that may be 15 used with facility for the suspension of the carton upon any suitable supporting wall surface.

Heretofore it has been the general custom to place paper towels in a metal container which requires the service of an attendant to reload 20 the cabinet at intervals, and to interlock the interfolded sheets. It is my purpose and object to provide a dispensing container that can be so cheaply made that it may be discarded when the 25 contents thereof have been withdrawn. 25

With these and incidental objects in view, the invention consists in certain novel features of construction and combination of parts, the essential elements of which are set forth in the appended claims, and a preferred form of embodiment of which is hereinafter shown with reference to the drawing which accompanies and forms a part of this specification.

In the drawing:

Fig. 1 is a perspective top front view of the 35 carton illustrating the slitted and scored outline of the dispensing opening in the front wall of the carton and adjacent its lower edge. In this view, the supporting ears are also shown slitted but in their normal lowered position. 40

Fig. 2 is a perspective front view of the dispensing carton illustrated in Fig. 1, but illustrating the dispensing opening resulting from the removal of that portion of the carton enclosed within the scored rectangle, and illustrating the 45 supporting ears in raised position. A fragment of a sheet ready for withdrawal is also shown.

Fig. 3 is a perspective front view of the carton illustrating one of the ends open and through 50 which the package of interfolded sheets is placed within the dispensing container, after which the end flaps of the carton are sealed, thereby sealing the pack of interfolded sheets within the carton.

Fig. 4 is a sectional end view of the carton 55

shown ready for the dispensing of the interfolded sheets therefrom.

Like reference characters refer to like parts through the several views.

5 I form my dispensing carton of inexpensive material as from a suitable paper product. I leave one end of the carton open as illustrated in Fig. 3 to facilitate the placing of a pack of interfolded sheets into the carton.

10 At the time of forming the carton blank I provide a central slit 1 and I score or otherwise perforate a pair of spaced lines 2 and 3 in the front wall of the carton and adjacent its front lower edge. The spacing of the lines 2 and 3 is sufficient 15 to permit a free pulling of the sheets of interlocked paper therethrough. I connect the oppositely disposed ends of the scored lines 2 and 3 with scored or perforated lines 5 and 6. The scored or perforated lines 5 and 6 are immediately adjacent the front vertical corners 7 and 8 of the carton.

15 At the time the carton is formed one end of the blank has a crease 9 disposed in spaced relationship with the crease that forms the lower 20 bottom front edge 4 of the carton and the crease 9 is in spaced relationship with the edge 10 of the sheet to provide a placement flap 11 that is in juxtaposition with the dispensing opening 12 that is provided by that portion 13 of the front wall 25 that lies within the rectangle outlined by scored or perforated lines. This placement flap prevents the premature emergence of the interfolded sheets and maintains the pack in place and position as the individual sheets are withdrawn 30 through the dispensing opening.

35 I place a pack of interfolded sheets within the carton at the point of origin of the product and seal the same therein by closing the end flaps 14 of the carton. The broad surfaces of the sheets lie in a vertical plane to thereby prevent the superposing of a load upon the sheets to be withdrawn from the carton as is unavoidable when the sheets are piled one upon the other with the broad surfaces of the sheets lying in a horizontal plane for withdrawal from the underside 40 of a dispensing cabinet. I outline by slits and perforations a pair of ears 15 and 16 in the top surface of the container and immediately adjacent the top rear edge 17.

45 When it is desired to suspend the carton upon a vertical wall the ears are raised as illustrated in Fig. 2. Supporting holes 18 and 19 are disposed in the ears and through which any suitable supports may be made to pass to suspend the same.

50 While the form of mechanism herein shown and described is admirably adapted to fulfill the objects primarily stated, it is to be understood that it is not intended to confine the invention to the embodiment herein shown and described, as it is susceptible of embodiment in various forms, all coming within the scope of the claims which follow.

55 What I claim is:

60 1. In a device of the class described, the combination of a parallelepipedon shaped container formed from a single piece of material, a rectangle outlined by perforations disposed on the front wall of said container, a plurality of ears 65 outlined by perforations disposed on the top wall of said container, a placement flap disposed within the container and so positioned as to be adjacent to and spaced apart from the front wall thereof and in alignment with the rectangle, and 70 a pack of interfolded sheets disposed within the

75 container, the folds in the sheets being horizontally disposed and the broad surfaces of the sheets being vertically disposed.

2. In a device of the class described, the combination with a box formed from a single piece 80 of material and containing a pack of interfolded sheets, of a rectangle outlined by perforations disposed on the front wall of the box, and a placement flap in juxtaposition with the rectangle, said placement flap being within the box and up- 10 standing from the base wall of the box.

15 3. In a device of the class described, the combination with a box formed from a single piece of fibrous material and containing a pack of interfolded sheets having horizontally disposed 15 folds and vertically disposed broad surfaces, of a rectangle outlined by perforations disposed on the front wall of the box, and a placement flap in juxtaposition with the rectangle, said placement flap being disposed within the box and upstanding 20 from the wall next adjacent the wall containing the rectangle.

25 4. In a device of the class described, the combination with a container formed from a single piece of material and containing a pack of interfolded sheets having horizontally disposed folds and vertically disposed broad surfaces, of a rectangle outlined by perforations disposed on the lower part of the front wall of the container, and a placement flap in juxtaposition with the rectangle, said placement flap being within the container and upstanding from the base wall of the 30 container.

35 5. In a device of the class described, the combination with a container formed from a single piece of fibrous material and containing a pack of interfolded sheets having horizontally disposed folds and vertically disposed broad surfaces, of a rectangle outlined by perforations disposed on the lower front wall of the container 40 and adapted to be torn therefrom, and a placement flap in juxtaposition with the rectangle, said placement flap being disposed within the container and upstanding from the wall next adjacent the wall containing the rectangle. 45

40 6. In a device of the class described, the combination with a container formed from a single piece of fibrous material and containing a pack of interfolded sheets having horizontally disposed folds and vertically disposed broad surfaces, of a rectangle outlined by perforations disposed on the lower front wall of the container and adapted to be torn therefrom, and a placement flap integral with the box and in juxtaposition with the rectangle, said placement flap 50 being disposed within the container and upstanding from the wall next adjacent the wall containing the rectangle.

55 7. In a device of the class described, the combination with a container formed from a single sheet of fibrous material, of a placement flap integral with the container and terminating the sheet from which the container is formed, said placement flap being disposed within the container and upstanding from one wall thereof, and 60 lying parallel to and adjacent the front wall of the container, and a strip outlined by perforations and disposed upon the front wall of the container.

65 8. In a device of the class described, the combination with a container formed from a single sheet of fibrous material, of a placement flap integral with the container and terminating the sheet from which the container is formed, and 70 lying parallel to and adjacent a wall of the con- 75

- tainer, and a strip outlined by perforations and disposed upon that wall of the container lying parallel to and adjacent the placement flap, and in juxtaposition with the placement flap.
- 5 9. In a device of the class described, the combination with a container formed from a single sheet of fibrous material, of a placement flap integral with the container and terminating the sheet from which the container is formed, and
- 10 lying parallel to and adjacent a wall of the container, and a strip outlined by perforations and disposed upon that wall of the container lying parallel to and adjacent the placement flap, and in juxtaposition therewith, said strip being
- 15 adapted for removal from the box as by tearing therefrom.
10. In a device of the class described, the combination with a container formed from a single sheet of fibrous material, of a placement flap integral with the container and terminating the sheet from which the container is formed, said placement flap being disposed within the container and upstanding from the base wall thereof, and lying parallel to and adjacent the front wall of the container, and a strip outlined by perforations and disposed upon the front wall of the 10 container, and in juxtaposition with the placement flap, said strip being adapted for removal from the box as by tearing, and a pack of inter-folded sheets having their folds, and their broad surfaces disposed parallel to the strip. 15

ROY L. PECK.
